UNITED STATES PATENT OFFICE.

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

LOOM-FRAME.

1,294,670.

Specification of Letters Patent. Patented Feb. 18, 1919.

Application filed September 15, 1917. Serial No. 191,514.

To all whom it may concern:

Be it known that I, JACOB KAUFMANN, a citizen of the United States, residing at Philadelphia, in the county of Philadelphia and State of Pennsylvania, have invented certain new and useful Improvements in Loom-Frames, of which the following is a specification.

My invention relates to loom frames, and it relates more particularly to the construction and arrangement of frames adapted to support reed dents, or heddles, in the loom. The principal object of my invention is to provide a simple and efficient, yet relatively inexpensive, construction of loom frames in which the dents or the heddles as the case may be, may be readily and quickly inserted or removed to permit changes in the count, and in which the dents or heddles will be firmly supported yet permitted to freely slide in the frame to accommodate themselves to the warp. My invention more specifically considered contemplates the provision of a loom frame having the top and bottom bars made of wood, fiber, or similar material and provided with interior slots for supporting the eyes of the dents or the heddles, as the case may be, which slots are accessible when desired for effecting changes in the arrangement of the number of dents or heddles supported in the frame.

The nature and characteristic features of my invention will be more readily understood from the following description taken in connection with the accompanying drawings forming part hereof, in which:

Figure 1 is a front elevation, partly broken away, of a loom frame embodying the main features of my invention, the same being shown in this instance as arranged for a false reed construction;

Fig. 2 is a top or plan view thereof; and

Fig. 3 is a transverse section of a portion of the frame shown in Fig. 1, the section being taken on the line 3—3 of Fig. 1.

Referring to the drawings, in the particular embodiment of my invention therein shown, the frame comprises top and bottom bars 5 made of wood, fiber, or similar material. At one end the top and bottom bars 5 are connected by means of a flat metal end bar 6 which extends across the

respective ends of the top and bottom bars 5 and is bent over as at 7 and rigidly secured on the outer edges of said top and bottom bars by means of screws 8. At the other end of each of the top and bottom bars 5 the same are connected by means of a flat metal end bar 9 which also extends across the ends of the top and bottom bars 5 and has its ends bent over as at 10 and these ends are pivotally secured on the outer edges of the top and bottom bars 5 by means of screws 11. The end bar 9 may be centrally reinforced by means of an additional bar 12 which may be riveted or otherwise secured to the end bar 9. The end bar 9 may be held in its closed operative position by suitably regulating the frictional tension of the screws 11.

Each of the top and bottom bars 5 is slotted as at 13 which slot extends from the inner edge of the bar 5 and communicates with an enlarged interior slot 14. The slots 13 and 14 of each bar 5 extend longitudinally the entire length thereof. The reed dents 15 extend through the slots 13 and are provided at their ends with enlarged eyes 16 which may be formed by bending the metal of the dent around to form the loop as clearly shown in Fig. 3 of the drawings. The eyes 16 of the dents are threaded on a rod 17 which extends from end to end within the slot 14 of the bar 5, and each end of the rod 17 may be provided with a nut 18 to retain the dents on the rods 17 and thus permit the entire group to be assembled before being mounted in the frame. Between the shoulders which are formed by the eyes 16 of the dents 15 and the adjacent surfaces of the slots 14 there are mounted on each side metal wires 19, which also extend from end to end within the slots 14 and form hard bearing surfaces for the eyes 16 of the dents 15 whereby the same will be permitted to freely slide within the frame to accommodate themselves to the arrangement of the warp.

As before stated the bent over ends 10 of the end bar 9 are pivotally secured to the outer edges of the top and bottom bars 5, and the purpose of this arrangement is to permit said end bars 9 to be swung outwardly to the position shown in dotted lines

in Fig. 2, and thereby permit access to interior of the slots 14 of said bars 5 and thus permit the ready insertion or removal of the entire group of the dents together with 5 the rods 17 upon which they are mounted.

It will be seen that there is thus provided a simple and efficient yet inexpensive construction of loom frames in which the top and bottom bars, may be made of wood, 10 fiber, or similar material in which however there will be provided bearing surfaces

- 10 for the eyes of the dents or heddles, permitting the same to freely accommodate themselves to the warp, and in which the 15 entire group of dents or heddles (which may be generically termed "warp controlling elements") in the frame may be readily and easily removed for the purpose of re-arrangement or replacement.

20 Having thus described the nature and characteristic features of my invention, what I claim as new and desire to secure by Letters Patent is:—

1. A loom frame comprising top and bottom bars having slots extending from the inner edges thereof and communicating with enlarged interior slots, said slots extending from end to end of said top and bottom bars, an end bar at one end having its ends bent 25 over and rigidly connected to the outer edges of the top and bottom bars, an end bar at the other end having its ends bent over and pivotally connected to the outer edges of the top and bottom bars, and warp controlling 30 elements slidably mounted at their ends in the enlarged interior slots.

2. A loom frame comprising top and bottom bars having slots extending from the inner edges thereof and communicating with 40 enlarged interior slots, said slots extending from end to end of said top and bottom bars, an end bar at one end having its ends bent over and rigidly connected to the outer edges of the top and bottom bars, an end bar at 45 the other end having its ends bent over and pivotally connected to the outer edges of the top and bottom bars, and warp controlling elements mounted in said frame having enlarged portions at each end mounted in the enlarged interior slots.

3. A loom frame comprising top and bottom bars having slots extending from the inner edges thereof and communicating with enlarged interior slots, said slots extending from end to end of said top and bottom bars, an end bar at one end having its ends bent 55 over and rigidly connected to the outer edges of the top and bottom bars, an end bar at the other end having its ends bent over and pivotally connected to the outer edges of the top and bottom bars, warp controlling elements 60 mounted in said frame having enlarged eyes 65

at each end mounted in the enlarged interior slots, and rods upon which said eyes are threaded.

4. A loom frame comprising top and bottom bars having slots extending from the inner edges thereof and communicating with enlarged interior slots, said slots extending from end to end of said top and bottom bars, an end bar at one end having its ends bent over and rigidly connected to the outer edges of the top and bottom bars, an end bar at the other end having its ends bent over and pivotally connected to the outer edges of the top and bottom bars, warp controlling elements mounted in said frame having enlarged eyes at each end mounted in the enlarged interior slots, and rods upon which said eyes are threaded having retaining means at each end.

5. A loom frame comprising top and bottom bars having slots extending from the inner edges thereof and communicating with enlarged interior slots, said slots extending from end to end of said top and bottom bars, an end bar rigidly connecting the top and bottom bars at one end thereof and closing one end of said slots, a movably attached end bar connecting said top and bottom bars at the other end thereof and normally closing said slots at said other end, 95 and warp controlling elements slidably mounted at their ends in the enlarged interior slots.

6. A loom frame comprising top and bottom bars having slots extending from the inner edges thereof and communicating with enlarged interior slots, said slots extending from end to end of said top and bottom bars, an end bar rigidly connecting the top and bottom bars at one end thereof and closing 100 one end of said slots, a movably attached end bar connecting said top and bottom bars at the other end thereof and normally closing said slots at said other end, and warp controlling elements mounted in said frame 105 having enlarged portions at each end mounted in the enlarged interior slots.

7. A loom frame comprising top and bottom bars having slots extending from the inner edges thereof and communicating with enlarged interior slots, said slots extending from end to end of said top and bottom bars, an end bar rigidly connecting the top and bottom bars at one end thereof and closing one end of said slots, a movably attached 115 end bar connecting said top and bottom bars at the other end thereof and normally closing said slots at said other end, warp controlling elements mounted in said frame having enlarged portions at each end 120 mounted in the enlarged interior slots, and wires forming bearing surfaces interposed between said enlarged portions and the adjacent surfaces of the interior slots.

8. A loom frame comprising top and bot-

- tom bars having slots extending from the inner edges thereof and communicating with enlarged interior slots, said slots extending from end to end of said top and bottom bars, an end bar rigidly connecting the top and bottom bars at one end thereof and closing one end of said slots, a movably attached end bar connecting said top and bottom bars at the other end thereof and normally closing said slots at said other end, warp controlling elements mounted in said frame having enlarged eyes at each end mounted in the enlarged interior slots, and rods upon which said eyes are threaded.
- 5 9. A loom frame comprising top and bottom bars having slots extending from the inner edges thereof and communicating with enlarged interior slots, said slots extending from end to end of said top and bottom bars, an end bar rigidly connecting the top and bottom bars at one end thereof and closing one end of said slots, a movably attached end bar connecting said top and bottom bars at the other end thereof and normally closing said slots at said other end, warp controlling elements mounted in said frame having enlarged eyes at each end mounted in the enlarged interior slots, rods upon which said eyes are threaded having retaining means at each end, and wires forming bearing surfaces interposed between said eyes and the adjacent surfaces of the interior slots.
- 10 10. A loom frame comprising top and bottom bars having slots extending from the inner edges thereof and communicating with enlarged interior slots, said slots extending from end to end of said top and bottom bars, an end bar rigidly connecting the top and bottom bars at one end thereof and closing one end of said slots, a movably attached end bar connecting said top and bottom bars at the other end thereof and normally closing said slots at said other end, warp controlling elements mounted in said frame having enlarged eyes at each end mounted in the enlarged interior slots, rods upon which said eyes are threaded having retaining means at each end, and wires forming bearing surfaces interposed between said eyes and the adjacent surfaces of the interior slots.
- 15 In testimony whereof I have hereunto signed my name.
- 20 JACOB KAUFMANN.
